INCLOSED FUSED SWITCH

Original Filed April 30, 1924 2 Sheets-Sheet 2

UNITED STATES PATENT OFFICE.

JOSEPH SACHS, OF WEST HARTFORD, CONNECTICUT.

INCLOSED FUSED SWITCH.

Application filed April 30, 1924, Serial No. 709,943. Renewed October 22, 1927.

This invention relates to the class of electrical devices in which each has a case or box inclosing an insulating base on which a switch for opening and closing the circuit and fuses for protecting the circuit are mounted, the switch and fuses being preferably connected in series. In a device of this class the fuses are covered and kept inaccessible from the exterior when the switch is closed by the obstruction offered by the switch handle to the opening movement of the cover over the fuses, and the fuses can only be uncovered and rendered accessible when the switch handle is moved to open the switch.

15 In my copending applications for Inclosed fused switches, Serial No. 528,934, filed Jan. 13, 1922 and Serial No. 656,182, filed Aug. 7, 1923, I have disclosed devices of the class referred to, each having an openable switch 20 cover and an additional means normally preventing access to the fuse but movable to permit access thereto, and each provided with a switch handle adjacent a side wall of the box and movable in a plane substantially parallel thereto, the relationship between the switch handle and the said additional means being such that the handle when in switch closing position obstructs a laterally movable portion of the said means to prevent movement of the 25 said means to the position permitting access to the fuses and the said relationship further being such that the said additional means when in the said access permitting position obstructs the movement of the handle from 30 switch opening position to switch closing position. In each of the devices as specifically disclosed in the said applications there is a switch cover and a fuse cover openable sidewise. The two covers are shown as hinged 35 directly to a side wall of the box, the opening movement of the fuse cover thus being a sidewise pivotal movement.

In accordance with the present invention I make use of the principle of a switch cover and an additional means for preventing access to the fuses provided with a portion having direct obstructive relationship with a switch handle movable in a plane parallel with the side of the box, and preferably I 45 construct the said means as a single cover openable sidewise; but in addition to these features I provide certain very important improvements. One object of the invention is to so construct the means for preventing 50 access to the fuses that at least a portion thereof, and if desired the entire means, is

rectilinearly movable parallelly with the front of the box and transversely of the path of movement of the switch handle for mutually obstructive purposes as described. 60

Another object of the invention is to provide a construction of the class described wherein the fuses are accessible through an opening in the main cover of the box when the said cover is closed to prevent access to the 65 switches and wherein the said additional means for preventing access to the fuses, obstructively related with the handle as described, is mounted directly on the said main cover. 70

A further object of the invention is to so connect the main cover that the said additional means thereon is bodily movable therewith when the said cover is opened, the said movement being permitted with the switch 75 handle in switch closing position and preferably with the switch handle in any position.

A still further object of the invention is to provide means for supporting the switch handle that it cannot be bent out of shape 80 and allow the auxiliary cover to be slid open when the switch is closed.

Further objects of the invention will be apparent from the following specification and claims. 85

In the accompanying drawings Fig. 1 shows a front view of one of the devices which embodies the invention. Fig. 2 shows a bottom elevation of the same. Fig. 3 shows a front view of the case with the main and auxiliary covers removed in order to expose the interior elements. Fig. 4 shows a vertical section on the dotted line 4—4 on Fig. 2. Fig. 5 is a detail view showing a modified way of obstructing the movement of the sliding auxiliary cover by the handle. 95

The case or box 1 may be made any size and shape and in any well known manner, and the main cover 2 can be fastened thereto by any usual means. The main cover is illustrated as attached to the case on one side by hinges 3 and secured on the other side by a perforated tongue 4 or latch through which a lock or seal may be passed, as is common. 100

The insulating base 5 may be supported in 105 the case in any desired way. Mounted adjacent the inner face of the base shown is a switch which may be varied as to details but which is shown as comprising swinging blades 6, rupture clips 7 and pivot clips 8. 110 Terminals 9 with binding screws 10 are connected with the rupture clips and conducting

strips 11 are connected with the pivot clips. On the outer face of the base are fuse receiving means, those illustrated being screw plug fuse shells 12, the center contacts 13 of which 5 are electrically connected with the strips 11 while the shells are electrically connected with terminals 14 provided with binding screws 15. The block illustrated is merely typical, there may be any number of switch 10 blades and any number of fuse receiving means of the desired character, depending upon the service to which the device is to be applied, as is well understood to those skilled in this art.

15 The switch blades are provided with insulating pieces 16 which are engaged by a crank rod 17 the ends of which extend through and are supported by the walls of the case. One end of the switch operating rod is extended 20 to provide a handle 18. The handle rod may be bent to form a loop as shown in Fig. 2 or may be left straight as shown in Fig. 5. In either case the handle includes a part 18^a which is movable in a plane substantially 25 parallel to the adjacent side wall of the box. For the sake of economy the switch operating element is desirably bent to shape from a single piece of rod or wire of relatively small diameter. To prevent the handle from 30 being distorted during use or by design, an inclosing bracket 19 may be secured to the side of the case in such manner that the outside wall will obstruct any attempt to bend the handle outward and the side walls will 35 form stops for limiting the movements of the handle. The side walls may also have perforations, as shown, through which a lock may be passed for fastening the handle in either its open or closed position.

40 The fuse receiving means, which may be of any well known type, are exposed through the opening 20 in the main cover. Associated with the opening 20 and carried by the main cover 2 is an additional means normally 45 serving to prevent access to the fuse contacts and movable independently of the said main cover to permit such access. The said additional means includes a portion which is rectilinearly movable parallelly with the front 50 of the box and transversely of the path of movement of the side part 18^a of the handle 18. The said transversely movable portion of the additional means is located in the path of movement of the side part 18^a of the handle whenever the said cover 2 is closed and the 55 said additional means is in position to permit access to the fuses, thus preventing movement of the handle from switch opening to switch closing position; and when the said 60 side part 18^a of the handle is in switch closing position it directly engages the said portion of the additional means to obstruct the rectilinear movement thereof and to thereby prevent movement of the said means to the 65 position permitting access to the fuses. The

details of the said additional means may be varied but preferably and in accordance with one phase of the invention I provide means which is in the form of a cover rectilinearly movable as an entirety laterally with respect 70 to the main cover.

When constructed as preferred there is provided a cover 21 which is attached to the main cover so as to slide sidewise or transversely thereto toward and from the path of 75 the switch operating handle. The auxiliary cover illustrated has flanges 22 at its lower edges which are fitted to slide under guide plates 23 fastened to the main cover. As illustrated the cover 21 is domed in order 80 to permit the fuses to project somewhat in front of the main cover and when the said cover is domed one end thereof is preferably open and is adapted to fit into and be closed by a head 24 secured to the main cover. The 85 end of the auxiliary cover toward the handle is closed. When the auxiliary cover is slid over the fuse receiving means its open end is closed and stopped by the head. In order to prevent the complete removal of the auxiliary cover when slid to expose the fuse receiving means it is provided with lugs 25 that are adapted to engage stop fingers 26 fastened to the main cover.

The switch operating handle is so shaped that when the switch is closed the handle extends up opposite the closed end of the auxiliary cover and prevents sidewise sliding of the auxiliary cover. When the switch is open the handle is turned down out of the path 100 of the auxiliary cover so that the auxiliary cover is free to be moved transversely and the fuse receiving means exposed for the insertion or removal of fuses. When the auxiliary cover is drawn out and the fuse receiving means are accessible it extends into the path of the handle so that the switch cannot be closed. It will be observed that when the fuse cover means simply comprises a cover such as 21 which is bodily movable laterally 105 as shown and described, the entire end part thereof, in this case the right-hand end part, serves as the aforesaid portion having direct 110 obstructive relationship with the switch handle.

In the form described the auxiliary cover is of substantially the same length as the width of the main cover and extends close to the path of the switch handle. If the auxiliary cover is shorter than the width of the main cover a plate 27 or other means may be secured to its closed end so as to extend out adjacent to the path of the handle, as illustrated in Fig. 5.

With this structure a fused switch can be 115 provided which, for example, may be connected to the service side of a meter and the switch at any time be operated from the exterior when the cover is closed and sealed to prevent access to the interior. With the slid- 120

able auxiliary cover arranged as described the fuses which are alive when in service, cannot be reached until the handle of the switch is turned down and the switch is open.

- 5 When the switch is closed the handle stands in front of the sidewise moving auxiliary cover over the fuses, and this handle although bent to shape of a single piece of rod cannot be distorted so as to permit the auxiliary cover 10 to be opened. This arrangement, in a simple and cheap manner, ensures safety in the manipulation of the fuses although they may be on the service side of an installation and are normally alive, for the fuses cannot be reached until the switch is open.

It will be observed that inasmuch as the handle is located entirely at one side of the box and that inasmuch as the fuse cover means is mounted entirely on the main cover 20 it is possible for the main cover to be opened with the switch handle in switch closing position or in fact with the switch handle in any position. I have thus provided an inclosed fused switch wherein, when the main cover 25 is closed and sealed, it is possible for unauthorized persons to obtain access to the fuses only when the switch is open; and at the same time the construction is such that an authorized person upon breaking the seal can obtain 30 access either to the switches or to the fuses or to both as may be required without opening the switch to interrupt the flow of current.

The invention claimed is:—

1. A fused switch comprising in combination, an inclosing box, fuse contacts in the box, a switch in the box, an exterior switch operating handle having at least one part thereof adjacent a side wall of the box and movable in a plane substantially parallel thereto, an openable front cover serving when closed to prevent access to the switch while permitting access to the fuse contacts, and means additional to the said cover normally serving to prevent access to the fuse 40 contacts and movable independently of the said cover to permit such access, the said means including a portion which is rectilinearly movable parallelly with the front of the box and transversely of the path of movement of the said part of the handle and which, whenever the first said cover is closed and the said additional means is in access permitting position, is located in the aforesaid path so that it directly obstructs movement of the 45 handle from switch opening position to switch closing position.
2. A fused switch comprising in combination, an inclosing box, fuse contacts in the box, a switch in the box, an openable front cover serving when closed to prevent access to the switch while permitting access to the fuse contacts, means additional to the said cover normally serving to prevent access to the fuse contacts and movable independently of the 50 said cover to permit such access, the said
- means including a portion which is rectilinearly movable parallelly with the front of the box and substantially perpendicular to the side walls thereof and which projects at one side of the box whenever the said cover is closed and the said additional means is in access permitting position, and an exterior switch operating handle having at least a part thereof adjacent the wall of the box at the last said side thereof and movable from switch closing position to switch opening position in a path which is directly obstructed by the said projectible portion of the said additional means when projecting as aforesaid, the said part of the handle when in switch closing position directly obstructing the rectilinear movement of the said projectible portion so as to prevent movement of the said means to access permitting position.
3. A fused switch comprising in combination, an inclosing box, an insulating base in the box, fuse receiving contacts on one face of the base, a switch adjacent another face of the base, an openable front cover serving when closed to prevent access to the switch while permitting access to the fuse contacts, means additional to the said cover normally serving to prevent access to the fuse contacts and movable independently of the said cover to permit such access, the said means including a portion which is rectilinearly movable parallelly with the front of the box and substantially perpendicular to the side walls thereof and which projects at one side of the box whenever the said cover is closed and the said additional means is in access permitting position, and an exterior switch operating handle having at least a part thereof adjacent the wall of the box at the last said side thereof and movable from switch closing position to switch opening position in a path which is directly obstructed by the said projectible portion of the said additional means when projecting as aforesaid, the said part of the handle when in switch closing position directly obstructing the rectilinear movement of the said projectible portion so as to prevent movement of the said means to access permitting position.
4. A switch device comprising in combination, an inclosing box, a switch in the box, a rectilinearly openable front cover for the box, the opening movement of the cover being parallel with the front of the box and substantially perpendicular to the side walls thereof so that a portion of the cover projects at one side of the box whenever the cover is open, and an exterior switch operating handle having at least a part thereof adjacent the wall of the box at the last said side thereof and movable from switch closing position to switch opening position in a path which is directly obstructed by a horizontal edge of the said projectible portion of the cover when in projecting position, the said side part of

the handle when in switch closing position being in the path of the said projectible portion of the cover and thus directly obstructing the opening movement thereof.

5. A fused switch comprising in combination, an inclosing box, fuse contacts in the box, a switch in the box, an openable front cover serving when closed to prevent access to the switch while permitting access to the 10 fuse contacts, an additional front cover normally serving to prevent access to the fuse contacts and rectilinearly openable independently of the first said cover to permit such access, the opening movement of the 15 cover being parallel with the front of the box and substantially perpendicular to the side walls thereof so that a portion of the cover projects at one side of the box whenever the first said cover is closed and the last said cover 20 is open, and an exterior switch operating handle having at least a part thereof adjacent the wall of the box at the last said side thereof and movable from switch closing position to switch opening position in a path which is directly obstructed by a horizontal edge of the 25 said projectible portion of the additional cover when in projecting position, the said side part of the handle when in switch closing position being in the path of the said projectible portion of the additional cover and thus directly obstructing the opening movement thereof.

6. An electric appliance comprising a case, a main cover with an opening therein and 35 sealable upon the case, an auxiliary cover mounted to slide on the main cover transversely thereof over the opening therein, an insulating base supported within the case, a switch mounted upon the base and inaccessible when the main cover is closed, fuse receiving means mounted upon the base accessible through the opening in the main cover and adapted to be enclosed by the auxiliary cover, the switch and fuse receiving means 40 being electrically connected, and means on the exterior of the case movable into and out of the path of the transversely sliding auxiliary cover for operating the switch and preventing the sidewise opening movement 45 of the auxiliary cover when the switch is closed.

7. An electric appliance comprising a case, a main cover with an opening therein and sealable upon the case, an auxiliary 55 cover mounted to slide on the main cover transversely thereof over the opening therein, an insulating base supported within the case, a switch mounted upon the base and inaccessible when the main cover is closed, 60 fuse receiving means mounted upon the base accessible through the opening in the main cover and adapted to be enclosed by the auxiliary cover, the switch and fuse receiving means being electrically connected, and a 65 handle on the exterior of the case for oper-

ating the switch, said handle extending into the path of and obstructing the sidewise opening movement of the auxiliary cover when the switch is closed, and lying out of the path of sidewise movement of the auxiliary cover when the switch is open.

8. An electric appliance comprising a case, a main cover with an opening therein and sealable upon the case, an auxiliary cover mounted to slide on the main cover 75 transversely thereof over the opening therein, an insulating base supported within the case, a switch mounted upon the base and inaccessible when the main cover is closed, fuse receiving means mounted upon the base 80 accessible through the opening in the main cover and adapted to be enclosed by the auxiliary cover, the switch and fuse receiving means being electrically connected, and a handle on the exterior of the case for operating 85 the switch, said handle extending into the path of and obstructing the sidewise opening movement of the auxiliary cover when the switch is closed, and lying out of the path of sidewise movement of the auxiliary cover 90 when the switch is open, and said auxiliary cover when slid sidewise obstructing and preventing the closing movement of the handle.

9. An electric appliance comprising a 95 case, a main cover with an opening therein and sealable upon the case, an auxiliary cover mounted to slide on the main cover transversely thereof over the opening therein, an insulating base supported within the case, a switch mounted upon the base and inaccessible when the main cover is closed, fuse receiving means mounted upon the base 100 accessible through the opening in the main cover and adapted to be enclosed by the auxiliary cover, the switch and fuse receiving means being electrically connected, a handle on the exterior of the case for operating the switch, said handle obstructing the sidewise opening movement of the auxiliary cover 105 when the switch is closed, and means attached to the case to prevent the outward bending of the handle.

10. An electric appliance comprising a 110 case, a main cover with an opening therein and sealable upon the case, said main cover having transversely extending ways, an auxiliary cover having flanges fitted to slide in said ways over the opening in the main cover, an insulating base supported within the case, a switch mounted upon the base and inaccessible when the main cover is closed, fuse receiving means mounted upon the base 115 accessible through the opening in the main cover and adapted to be enclosed by the auxiliary cover, the switch and fuse receiving means being electrically connected, and a handle on the exterior of the case for operating the switch, said handle extending into 120 the path of the transversely sliding auxil- 125 130

iary cover and obstructing the sidewise movement of the auxiliary cover when the switch is closed, and lying out of the path of sidewise movement of the auxiliary cover 5 when the switch is open.

11. An electric appliance comprising a case, a main cover with an opening therein and sealable upon the case, an auxiliary cover mounted to slide on the main cover transversely thereof over the opening therein, a switch mounted in the case, fuse receiving means mounted in the case and accessible through the opening in the main cover and adapted to be enclosed by the auxiliary cover, the switch and fuse receiving means being electrically connected, and a handle on the exterior of the case for operating the switch said handle extending into the path of and obstructing the sidewise opening 20 movement of the auxiliary cover when the switch is closed.

12. An electric appliance comprising a case provided with a main cover having an opening, a sidewise sliding auxiliary cover over said opening, a base supported in the case, a switch and fuse receiving contacts on said base, the fuse receiving contacts being accessible through the opening in the main cover when the auxiliary cover is open and 30 inaccessible when the auxiliary cover is closed, and means accessible on the exterior of the case for operating the switch, the exterior portion of the switch operating means and the auxiliary cover being so related that by direct engagement of and obstruction by one with the other the opening of the auxiliary cover is prevented when the switch is closed, and closing of the switch is prevented when the auxiliary cover is 40 open.

13. An electric appliance comprising a case provided with a main cover having an opening, a sidewise sliding auxiliary cover over said opening, a base supported in the case, a switch and fuse receiving contacts on said base, the fuse receiving contacts being accessible through the opening in the main cover when the auxiliary cover is open and inaccessible when the auxiliary cover is 45 closed, means accessible on the exterior of the case for operating the switch, the exterior portion of the switch operating means and the auxiliary cover being so related that opening of the auxiliary cover is prevented when the switch is closed, and closing of the switch is prevented when the auxiliary cover is open, and means attached to the case adjacent to the switch operating means to prevent the distortion of the exterior portion of the switch operating means. 55

14. A fused switch comprising in combination, an inclosing box, fuse contacts in the box, a switch in the box, a front cover for the box normally serving to prevent access to the switch, the said cover having an opening 65 to the switch, the said cover having an open-

ing therein for permitting access to the fuse contacts, additional means carried by the first said cover and normally serving to prevent access to the fuse contacts, the said means being movable independently of the said cover to permit access to the fuse contacts and including a laterally movable portion which projects at one side of the box whenever the said cover is closed and the said additional means is in access permitting position, and an exterior switch operating handle having at least a part thereof adjacent the wall of the box at the last said side, the said part of the handle being movable from switch closing position to switch opening position in a path which is directly obstructed by the said projectible portion when in projecting position and the said part of the handle when in switch closing position being in the path of the said projectible portion and thus directly obstructing the movement of the said additional means to access permitting position, and means connecting the said cover with the box so as to permit forward opening movement thereof and of the said additional means with the switch handle in switch closing position. 85

15. A fused switch comprising in combination, an inclosing box, fuse contacts in the box, a switch in the box, a front cover for the box normally serving to prevent access to the switch, the said cover having an opening therein for permitting access to the fuse contacts, a second front cover carried by the first said cover and normally serving to prevent access to the fuse contacts, the said second cover being openable independently of the first said cover to permit access to the fuse contacts and including a laterally movable portion which projects at one side of the box whenever the first said cover is closed and the second said cover is open, and an exterior switch operating handle having at least a part thereof adjacent the wall of the box at the last said side, the said side part of the handle being movable from switch closing position to switch opening position in a path which is directly obstructed by the said projectible portion of the second cover when in projecting position and the said side part of the handle when in switch closing position being in the path of the said projectible portion of the second cover and thus directly obstructing the opening movement thereof, and means connecting the first said cover with the box so as to permit forward opening movement of both covers with the switch handle in any position. 110

16. A fused switch comprising in combination, an inclosing box, fuse contacts in the box, a switch in the box, a front cover for the box normally serving to prevent access to the switch, the said cover having an opening therein for permitting access to the fuse contacts, an additional front cover carried 125

by the first said cover and normally serving to prevent access to the fuse contacts, the said second cover being openable independently of the first said cover to permit access 5 to the fuse contacts and having its opening movement parallel with the front of the box and substantially perpendicular to the side walls thereof so that when in the open position a portion projects at one side of the first 10 said cover, an exterior switch operating handle carried by the box independently of the covers and having at least a part thereof adjacent the wall of the box at the last said side, the said side part of the handle being 15 movable from switch closing position to switch opening position in a path which is directly obstructed by the said projectible portion of the fuse cover when in projecting position and the said side part of the 20 handle when in switch closing position being in the path of the said projectible portion of the second cover and thus directly obstructing the opening movement thereof, and means connecting the first said cover 25 with the box so as to permit forward opening movement of both covers with the switch handle in switch closing position.

17. A fused switch comprising in combination, an inclosing box, fuse contacts in the box, a switch in the box, an exterior switch operating handle having at least one part thereof adjacent a side wall of the box and movable in a plane substantially parallel thereto, an openable front cover serving when closed to prevent access to the switch while 30 permitting access to the fuse contacts, means additional to the said cover normally serving to prevent access to the fuse contacts and movable independently of the said cover to permit such access, the said means including 35 a portion which is rectilinearly movable parallelly with the front of the box and transversely of the path of movement of the said part of the handle and which, whenever the first said cover is closed and the said additional means is in access permitting position, is located in the aforesaid path so that it 40 directly obstructs movement of the handle from switch opening position to switch closing position, and means attached to the box 45 adjacent to the switch operating means to prevent the distortion of the exterior portion of the switch operating means.

JOSEPH SACHS.
